UNITED STATES PATENT OFFICE.

PETER PAULUS AND HENRI FABER, OF MILWAUKEE, WISCONSIN.

WINDOW-SCREEN.

SPECIFICATION forming part of Letters Patent No. 334,676, dated January 19, 1886.

Application filed September 28, 1885. Serial No. 178,391. (No model.)

To all whom it may concern:

Be it known that we, PETER PAULUS and HENRI FABER, both residents of Milwaukee, in the county of Milwaukee and State of Wisconsin, have invented certain new and useful Improvements in Window-Screens; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a portion 15 of a window-frame provided with our improved fly-screen, showing the hinged portion of the screen opened and the screen drawn out to its full width. Fig. 2 is a front view of the same with the hinged portion closed and the frame 20 drawn in to less than its full width, and Fig. 3 is a perspective detail view of one of the sliding sides of the screen and the means for adjusting the parts of the same.

Similar letters of reference indicate corresponding parts in all the figures.

Our invention has relation to that class of extensible window-screens in which the rabbed or reduced ends of the top and bottom pieces of the frame-halves slide upon each 30 other, the top and bottom pieces of one frame-half having longitudinal slots with which they slide upon set-screws projecting from the other top and bottom pieces; and it consists in the improved construction and combination of 35 parts of such a screen in which the slots in the top and bottom pieces may be covered, so as not to admit any insects, and which may be permanently secured in the window-frame and still be capable of being opened, as hereinafter 40 more fully described and claimed.

In the accompanying drawings, the letters A and B indicate the frame-halves, the top and bottom pieces of which are reduced for a portion of their length, as shown at C and D, 45 for the purpose of fitting upon each other. The end pieces, E and F, of the screens are provided with perforations for the reception of screws G, by means of which the frame-halves are secured to the jambs of the window-frame. The reduced portions C of the top and bottom pieces of the frame-half A are formed 50 with longitudinal slots H H, through which

project screws I I from the reduced ends of the top and bottom pieces of the other frame-half, B, the said slots sliding upon the screws, 55 and the screws are provided with thumb-nuts J, bearing against the inner sides of the slotted portions, for the purpose of clamping them and adjusting them upon the screws. The frame-half A is provided with a frame, K, 60 which fits within the sides of the frame, and which is covered with net L, and this inner frame is hinged at its outer side to the end piece of the frame-half swinging inward. Turn-buttons M are pivoted upon the screws, and 65 serve to retain the hinged frame closed, and may be secured in their position by tightening the thumb-nuts. Strips N, of tin or similar sheet metal, are pivoted upon the screws at one end, and are of a sufficient length to cover 70 the ends of the slots, which are left open by sliding the screen-halves out, the strips being turned from their resting-place in the rabbets of the top and bottom pieces of the frame B to the rabbets in the top and bottom pieces of 75 frame A when the frame-halves are slid apart. It will thus be seen that the frame may be fitted into almost any size of window-frame, whereupon the end pieces of the frame may be secured by the screws in the said window-frame, and whenever it is desired to have access through the window the hinged frame of the screen may be swung inside.

We are aware that it is old to construct an adjustable window-screen composed of two sliding frame-halves, one of the said frame-halves having its top and bottom pieces formed with longitudinal slots and the other frame-half having its top and bottom pieces provided with screws, which project through the slots 80 of the other frame-half and have nuts upon their free ends, by means of which the frame-halves are secured in their adjusted positions, and the said top and bottom pieces being formed with projections adapted to close the 85 slots of the slotted frame-half when the screens are extended, for the purpose of excluding insects; and we are also aware that it is old to hinge one half of a screen to the end bar of an integral frame, and we do not therefore claim 90 either of such constructions, broadly; but

What we claim as our invention, and desire to secure by Letters Patent of the United States, is—

1. In an extensible window-screen; the combination of a frame-half having the ends of its top and bottom pieces reduced and formed with longitudinal slots, a frame-half having the ends of its top and bottom pieces reduced and sliding upon the other reduced ends, and provided with screws projecting through the slots and having thumb-nuts, and strips of tin pivoted at their ends upon the screws between the reduced ends of the top and bottom pieces of the frame-halves, as and for the purpose shown and set forth.

2. In an extensible window-screen, the combination of a frame-half having the ends of its top and bottom pieces reduced and longitudinally slotted, a frame-half having the ends of its top and bottom pieces reduced, and pro-

vided with screws projecting through the slots and having thumb-nuts, strips of sheet metal pivoted at one end upon the said screws between the reduced ends, a screen hinged to the end piece of one frame-half, and turn-buttons pivoted upon the screws and holding the hinged screen closed, as and for the purpose shown and set forth.

In testimony that we claim the foregoing as our own we have hereunto affixed our signatures in presence of two witnesses.

PETER PAULUS.
HENRI FABER.
